BUTTON ATTACHMENT FOR SEWING MACHINES

Efim M. Shevchik, Orange, N. J.

Application December 6, 1950, Serial No. 199,404

5 Claims. (Cl. 112—108)

1

This invention relates to improvements in button attachments for sewing machines and relates more particularly to such attachments as are used on power machines employed in the manufacture of garments.

The principal object of the invention is the provision of a device which has a wall extending upwardly from the foot portion and having therein a passage to receive the shank or stem of the button, so that as a button is firmly held against this wall with its stem positioned in said passage, the stem is in the correct position to have the needle of the machine to pass vertically down through it, and the fabric to which the button is to be sewn, during one stroke and to have the needle clear the end of said stem during the next stroke, so that the length of the bundle of threads on the opposite face of the fabric is no longer than the spacing of the two paths of the needle.

Another object of the invention is the provision of said upwardly extending wall both as a firm support against which the buttons are pressed, and also as a safety device which positively prevents the fingers of an operator from getting into the range of the needle.

Yet another object of the invention is the provision of an improved support for the garment, or other work, beneath the foot of my device, which insures faster application of the buttons to the garment and the disposal of the buttons in a neater array.

Another object of the invention is the formation of a single blank form which is adapted to be cut out to accommodate any given size and style of button, so that as new styles, types, and size are encountered, devices embodying the features of the invention may be easily made up.

Other objects and advantages of the invention will be apparent to those skilled in the art upon a study of this specification and the accompanying drawings.

Referring to the drawings, which are given by way of example to teach others to practice the invention;

Figure 1 is a perspective view of one form of button attachment of the prior art;

Figure 2 is a perspective view of another form of button attachment of the prior art;

Figure 3 is a side elevation of my improved device taken along the line 3—3 of Figure 4;

Figure 4 is an end elevation of my device taken along the line 4—4 of Figure 3;

Figure 5 is a side elevation as seen along the line 5—5 of Figure 4;

Figure 6 is a bottom view as seen along the line 6—6 of Figure 3;

2

Figure 7 is an end elevation as seen along the line 7—7 of Figure 3;

Figure 8 is a plan view as seen along the line 8—8 of Figure 5;

Figure 9 is a sectional elevation taken along the line 9—9 of Figure 5;

Figure 10 is a perspective view of a portion of a machine with my improved device mounted thereon and showing a button positioned in contact with the vertical wall thereof with its shank or stem positioned in the passage which extends through said wall;

Figure 11 is an elevation, partly in section, showing a button being sewn on to a fabric, and showing my improved support for the garment or other work;

Figure 12 is an elevational view, taken along the line 12—12 of Figure 11;

Figure 13 is a side elevation of my improved work support;

Figure 14 is a plan view of the work support shown in Figure 13;

Figure 15 is a perspective view of my new device in blank form;

Figure 16 is a view of the opposite face of a piece of fabric after a button has been applied thereto with my device; and

Figure 17 is a view of the opposite face of a piece of fabric after a button has been sewn thereon utilizing the prior art device shown in Figure 2.

In the prior art there are two general forms of button devices. One of them is shown in Figure 1 and designated by the numeral 20. It has a vertical plate portion 21 which is slotted for attachment to the machine, and a horizontal plate portion with a notch 23 therein to accommodate the stem or shank of the button, and a slot 24 communicating therewith for the needle. With this device, there is nothing to guide the operator as to whether the button is straight or not, and also there is nothing to keep the fingers of the operator out of the path of the needle.

The other form is shown in Figure 2, and designated by the numeral 25. It has a vertical plate portion 26 which is slotted for attachment to the machine, and has a horizontal plate portion 27 formed integral therewith. Extending downwardly from the left edge of the portion 27 are parallel portions 28 and 29 with a space 30 between them. A slot 31 in the portion 27 flares outwardly and joins the space 30 which is widened at 32 to accommodate the stem or shank of the button. With this device a work support 33 in the form of a rod having a slotted end is employed. The fabric to which the button is to

be sewn is shown at 34 in Figure 2, and the reverse side of this fabric, after the button 35 has been applied, is shown in Figure 17. The bundle of threads 36 securing the button is not only objectionably long but it wastes thread.

In this form, the portions 28 and 29 do tend to guide the button straight, but the position is awkward and there is nothing to prevent the operator's fingers from getting into the path of the needle.

According to my invention, referring first to Figures 3 to 9 inclusive, my device 40 comprises an L-shaped member and a vertical plate portion 37 having a vertical slot 38 formed therein for attachment to the machine. Formed integral with the portion 37 is a horizontal portion 41 which has a laterally extending slot 42 therethrough, through which the needle passes to engage the shuttle. The portion 41 also has a depression 43 formed therein, centralized with respect to the axis of the slot.

Preferably formed integral with the horizontal portion 41, although it may be made of a separate piece of material secured thereto, is an upstanding vertical wall 44 which has a passage 45 therethrough of a shape and size to accommodate the shank or stem of the button. Since the central horizontal plane of this passage is substantially level with the upper surface of the portion 41, an extension 45a of this passage 45 is formed in the portion 41 and communicates with the depression 43, as may be seen in Figure 9. In Figure 5 the passage 45 is shown as somewhat oval in form, but it will be understood that this passage may be of any other shape, to accommodate the shank of any type or style of button to be used.

A vertical slot 46 is formed in the portion 44, and it communicates with the passage 45 and with a depression 47 also formed in the portion 44. This depression extends through the upper edge of the portion 44, leaving a narrow web of material 47a and thereby providing ample clearance for the needle.

Referring to Figures 11 and 12, I show one of my new devices described above, and its relative position with respect to a work support 50. A button 49 is placed on the device with its shank 51 positioned in the passage 45 with the hole 52 therein extending vertically in line with one path 53a of the needle. The needle when moving vertically along its second path 53b clears the end of the shank 51. It will be noted that the work 48 is horizontally disposed and consequently the length of the bundle of threads 54 (Figure 16) on the opposite face of the work is approximately equal to the distance apart of the needle paths 53a and 53b, and thereby a neater job is performed and a substantial sewing of thread is effected.

The work support 50, which may be also seen in Figures 13 and 14 is preferably comprised of a stamping having an open slot 54 extending in from one end, and oppositely disposed depending locating tabs 55 and 56. Adjacent to the other end is an elongated slot 57 which extends axially of the support and provides clearance for the needle. On said last end is a depending tab 58, the inner surface of which is beveled. This work support is secured on a shaft element 59 by means of a screw 61, and due to the slot 54, which rides the screw, the end 58 may be set in any desired position relative to my device.

In Figure 15, I show my improved blank, designated by the numeral 60. The vertical plate

portion 37 has the attachment slot 38 formed therein, and the portions 41 and 44 are blank so that they may be formed to accommodate practically any type of button.

Although I have herein shown and described by way of example one embodiment of my invention, it will be understood that many variations in the device, shown and described, are within the scope of the appended claims.

10 I claim:

1. A foot for a button sewing machine comprised of an L-shaped member the bottom wall of which is horizontally disposed and the other wall of which extends upwardly, an attachment portion formed integral with said bottom wall and disposed substantially 90° with respect to both said walls, said walls and said attachment portion being formed of a single piece of material of uniform thickness, socket means extending laterally through said other wall and centralized on a plane substantially on the same level as the upper surface of said bottom wall, a clearance depression for a portion of said shank formed in said bottom wall, and needle clearance slots formed in both said walls.

2. In a foot for a button sewing machine, a slotted vertical plate portion for attachment to said machine, a vertically disposed wall portion extending horizontally from said plate portion, 30 at least said plate portion and said wall portion being extremely rigid relative to one another, socket means for the shank of a button extending through said wall portion, whereby a button may be firmly pressed against one face of said wall with its shank extending into said socket, a vertically disposed passage formed in the opposite face of said wall to clear a needle in said machine, and a horizontal plate formed integral with and forming a common support for both said plate portion and said wall portion.

3. A work support for attachment on a button sewing machine, said support having a flat portion to be horizontally disposed in said machine, a mounting slot extending inwardly from one end of said support, spaced depending locating tabs adjacent to said last end, a needle clearance slot adjacent to the other end thereof and in axial alignment with said first slot, and a depending tab on the other end of said support having its inner surface beveled.

4. A foot for a button sewing machine comprised of an L-shaped member, the bottom wall of which is horizontally disposed and the other wall of which extends upwardly, an attachment portion formed integral with said bottom wall and disposed substantially 90° with respect to both said walls, said walls and said attachment portion being formed of a single piece of material of substantially uniform thickness, a work support in combination with said foot including means for mounting the same on said machine, a flat horizontal web having a needle clearance slot formed therein, and a depending end tab adapted to be set in alignment with one face of said other wall.

5. In a device of the character described, an L-shaped member having a base wall horizontal and having its other wall vertical, socket means to accommodate the shank of a button formed in part in said vertical wall and formed in part in said base wall, needle clearance slots formed in both said walls and lying on a common plane, and an extension on said channel for attachment to a button sewing machine, both the walls of 70 said channel and the extension all being of sub-

stantial thickness to impart extreme rigidity thereto and all thicknesses of said walls and said extension being substantially the same to make them immobile relative to one another.
